[57] CLAIM

The ornamental design for a combined rotating cafeteria food service counter and cap, substantially as shown and described.

DESCRIPTION

FIG. 1 is a front elevational view of a rotating cafeteria type food service counter and cap showing my new design;

FIG. 2 is a top plan view of the embodiment shown in FIG. 1;

FIG. 3 is a right side elevational view of the embodiment shown in FIG. 1, with the left side elevational view being a mirror image of the right side elevational view;

FIG. 4 is a rear elevational view of the embodiment shown in FIG. 1;

FIG. 5 is a cross sectional view taken along line 4—4 of FIG. 1; and

FIG. 6 is a bottom view of the embodiment shown in FIG. 1.
